UNITED STATES PATENT OFFICE.

FREDERICK H. MILES AND JUDSON D. SWITZER, OF PORTLAND, OREGON.

REVERSIBLE CASEMENT WINDOW.

Application filed April 7, 1927. Serial No. 181,784.

The invention relates to casement windows of the type in which the sash is reversible, permitting easy cleaning of its outer side without danger or exposure.

5 Specifically, the invention relates to reversible casement windows in which the sash is provided with bearings rotatably receiving a shaft whose ends are provided with pinions engaging frame-carried rack bars, 10 said pinions traveling along said rack bars as the sash is moved to either of its relatively reversed positions; and one aim of the invention is to provide means for locking the shaft against turning with respect to the 15 sash when desired, thereby holding the pinions against traveling along the rack bars. Thus, when the sash is in a desired open position, it cannot shift toward either side of the frame and it may be held against 20 swinging by conventional means.

A further object of the invention is to provide novel means for mounting a bolt which is used to lock the shaft in the manner above referred to.

25 Still another aim is the provision of unique and advantageous means for mounting the sash and holding the pinions in mesh with the rack bars.

With the foregoing in view, the invention 30 resides in the novel subject matter herein-after described and claimed, the description being supplemented by the accompanying drawings.

Fig. 1 is a side elevation of a window constructed in accordance with our invention.

Fig. 2 is an enlarged vertical sectional view partly broken away.

Fig. 3 is a vertical transverse section on line 3-3 of Fig. 2.

40 Figs. 4, 5, 6, 7 and 8 are horizontal sectional views on the correspondingly numbered lines of Figs. 2 and 3.

Fig. 9 is a perspective view of one of the outer U-shaped plates used in producing the 45 shaft bearings.

Fig. 10 is a perspective view of the inner U-shaped plate which co-operates with the outer U-shaped plate in producing the upper shaft bearing.

50 Fig. 11 is a perspective view of the inner U-shaped plate which co-acts with the outer U-shaped plate in producing the lower bearing and providing means for mounting the bolt.

55 Fig. 12 is a side elevation partly in sec-

tion, of the tubular pinion-carrying shaft and its bearings.

In the drawings above briefly described, a frame F is shown, whose upper portion U is provided with two parallel, horizontally spaced rails 14, preferably formed of T-iron, the ends of these rails being spaced apart by sleeves such as 15, of Figs. 2 and 3, tie-bolts 16 being passed through said rails and sleeves. A horizontally disposed rack bar 60 17, is positioned below one of the rails 14 and extends from one vertical side of the frame to the other, said rack bar being mounted on suitable means 18, secured to said rail. This means 18 may either consist of a single angular plate or of a plurality of angular straps, as occasion may dictate.

The lower portion L of the frame F, embodies a transversely arched sill 19, a horizontal rack bar 20 spaced above said sill, 75 carrying means 21 for said rack bar, suitably secured to the sill, and a rail 22 spaced below and spaced horizontally from said rack bar.

A vertical shaft 23 extends from the upper 80 to the lower portion of the window frame and is provided with means engaging the rails 14 and 22. Preferably, the upper end of said shaft is formed with a head 24 having rollers 25 resting upon the inwardly extending flanges of the rails 14, so that the weight of the shaft 23 and all parts associated therewith, will be anti-frictionally suspended. At its lower end, the shaft 23 is provided with a shoe 26 which engages 85 the inner side of the rail 22 and serves to hold the shaft against turning, said shoe being provided with a flat, rail-engaging surface for this purpose.

90 A tubular shaft 27 rotatably surrounds the shaft 23 and is provided at its upper and lower ends with pinions 28-28^a, meshing with the rack bars 17-20, an anti-friction bearing 29 being preferably interposed between the lower end of said shaft 27 and the shoe 26, so that the weight of said shaft 27 is anti-frictionally carried by the shaft 23. Due to the mounting of shaft 23, it cannot laterally shift away from the rack bars 17-20 and hence the pinions 28-28^a, are held in mesh with said rack bars.

95 30 denotes the sash, said sash being provided with upper and lower bearings which are denoted in a general way at 31 and 31^a respectively, and between these bear-

ings and the pinions 28—28^a, anti-friction bearings 32—32^a are preferably employed. In the present showing, the sash 30 is of hollow, metal construction and the bearings 31—31^a are provided with anchoring portions 33—33^a which are snugly secured in end portions of the upper and lower rails 34—34^a of said sash. The shafts 23—27 are received in one of the hollow vertical rails 35 10 of the sash 30, and this rail is provided with a detachable section 36 opposed to the adjacent ends of the rails 34—34^a. This section 36 is detachably secured to the body portion of the rail 35, by screws 37, and other screws 15 38 may be employed to secure the anchoring portions 33—33^a of the bearings 31—31^a rigidly within the rails 34—34^a.

The detachable rail section 36, the location of the shafts 23—27 in the vertical rail 35, 20 and the detachable anchoring of the portions 33—33^a of the bearings, in the rails 34—34^a, is of great advantage in assembling or disassembling for repairs, as well as producing a compact, protected, durable and efficient 25 construction.

The bearings 31—31^a, possess a number of features in common and hence the same description, with some variations, will suffice for both of them. In connection with this 30 description, see more particularly Figs. 5 to 11 inclusive.

39 denotes an outer substantially U-shaped plate whose bight portion engages the shaft 27, while its arms project in the same direction from said shaft in spaced parallel relation with each other. The inner end portion of this plate, for the upper bearing 31, is formed with a notch 40 to accommodate the pinion 28, and a similar notch 40^a is formed in the plate 39 for the lower bearing 31^a, for a purpose to appear.

An inner U-shaped plate 41 is received snugly between the arms of the plate 39 and the arms of the two plates are secured together by screws or the like 42^a. The bight portion 42 of this plate 41, is shaped to co-operate with the corresponding portion of the plate 39, in forming a complete bearing for the shaft 27, and the plates 39—41 have 50 their arms bent to provide co-operating shoulders 43—43^a, which limit the movement of their bight portions toward each other, so that they cannot bind upon the shafts.

The end of the U-shaped plate 41, toward 55 the shaft 27 (upper bearing 31) is notched at 44 to accommodate the pinion 28. The corresponding portion of the lower bearing 31^a is notched at 44^a and this notch communicates with the notch 40^a as shown in Fig. 5, the two notches accommodating a collar 45 which is suitably secured upon the shaft 27, for a purpose to appear.

The notch 44^a is formed by bending portions of the arms of the lower plate 41, inwardly toward each other as shown at 46 in

Figs. 5 and 11. Moreover, these arms of both of the plates 41, have their free ends bent inwardly toward each other as shown at 47. The portions 46—47 of the plate 41 (lower bearing 31^a) are formed with alined 70 openings in which a tube 48 is secured. This tube contains a bolt 49 which, by appropriate operating means 50, may be projected into any of a plurality of notches 51 with which the collar 45 is formed. When the bolt 49 75 is engaged with any of these notches, the shaft 23 is held against turning with respect to the sash 30. Thus, the sash cannot bodily shift from one side of the frame F toward the other side thereof, for instance, under 80 the influence of wind, after it has once been set at a desired position. To then prevent the pinions 28—28^a from rolling along the 85 rack bars 17—20, a conventional sash-holding device such as that shown at D in Fig. 1, may be employed, said device being of course detachably connected with the sash 30 so that it will not interfere with reversal of the latter when desired.

Normally, the bolt 49 is disengaged from the collar 45. Thus, when the sash 30 is to be reversed for cleaning, it may be swung open and its pivoted end then forced toward the side of the frame F, opposite that side at which said pivoted end was previously 95 disposed. During this movement, the pinions 28—28^a roll along their respective rack bars and when they have reached their other extreme positions, the sash may again be swung closed, giving access to what was previously its outer side, for effectively cleaning the same without danger and without exposure to the weather.

For ventilating purposes, it is often desirable to shift the shafts 23—27 to a position between the vertical sides of the frame and to swing the sash at an angle to the plane of the frame. The bolt 49 and one or another of the notches 51, together with the device D, serve to effectively hold the 110 sash in its adjusted position.

As excellent results are obtainable from the details disclosed, they are preferably followed. However, within the scope of the invention as claimed, variations may be 115 made, and by slight changes, wood instead of metal, may be used for the sash and certain frame parts.

We claim:

1. In a reversible casement window a 120 frame, rack bars extending along the upper and lower portions thereof, pinions meshing with said rack bars, a vertical shaft carrying said pinions, a sash having bearings in which said shaft is rotatable, and means for locking the sash to the shaft to prevent rotation of the latter with respect to said sash when desired.

2. In a reversible casement window, a 130 frame, rack bars extending along the upper

and lower portions thereof, pinions meshing with said rack bars, a vertical shaft carrying said pinions, a sash having bearings in which said shaft is rotatable, a bolt carried by one of said bearings and movable toward and from said shaft, and means at the periphery of said shaft for engagement with said bolt to prevent rotation of the shaft with respect to the sash when desired.

19. 3. In a reversible casement window, a frame having horizontal rack bars along its upper and lower portions, a vertical shaft having pinions meshing with said rack bars, a sash having a hollow frame one of whose 15 vertical rails receives said shaft, upper and lower bearings for said shaft having anchoring portions secured snugly in end portions of the upper and lower rails of the sash, the lower bearing being provided with a horizontal bolt guide, a bolt slideable in said 20 guide, means at the periphery of the shaft engageable with said bolt to lock the shaft against turning with respect to the sash when desired, and operating means for said 25 bolt extending to the inner side of the sash.

4. In a reversible casement window, a frame having horizontal rack bars along its upper and lower portions, a vertical shaft having pinions meshing with said rack bars, 30 a sash having a hollow frame one of whose vertical rails receives said shaft, upper and lower bearings for said shaft having anchoring portions secured snugly in end portions of the upper and lower rails of the sash, 35 said anchoring portion of one of said bearings comprising vertical side plates and transverse vertical members extending between them, said vertical members having horizontally aligned openings, a tube secured 40 in said openings, and a manually controlled bolt slideable in said tube for engagement with the shaft to hold the latter against turning with respect to the sash when desired.

45. 5. In a reversible casement window, a frame having horizontal trackage along its upper and lower portions, a vertical shaft extending from the upper to the lower portion of the frame and having means at its 50 ends engaging said trackage for movement along the same, a tubular shaft rotatably surrounding the first named shaft and having pinions at its ends, stationary rack bars extending horizontally along said upper and 55 lower portions of the frame and meshing with said pinions, and a sash having bearings rotatably receiving said tubular shaft.

6. In a reversible window, a frame having

parallel horizontally spaced rails along its upper portion and a horizontal rack bar 60 below one of said tracks, the lower portion of the frame being provided also with a horizontal rack bar and with a horizontal rail below, laterally spaced from and parallel with this rack bar, a vertical shaft whose upper end is disposed between said parallel rails and provided with supporting shoes 65 engaging the same, the lower end of said shaft being provided with a shoe engaging the inner side of the lower rail, a tubular 70 shaft rotatably surrounding the first named shaft and having pinions meshing with said rack bars, and a sash having bearings rotatably receiving said tubular shaft.

7. In a reversible casement window, a 75 pivot shaft, a substantially U-shaped plate whose bight portion receives said shaft and whose arms project laterally from the same, a second substantially U-shaped plate snugly fitting between said arms and having its 80 bight portion shaped for co-action with the first named bight portion to provide a bearing for the shaft, and means for securing the two plates together.

8. A structure as specified in claim 7; the 85 arms of the two U-shaped plates being bent to provide abutting shoulders limiting the movement of said bight portions toward each other.

9. A structure as specified in claim 7; the 90 arms of the second U-shaped plate having transverse inwardly bent portions at their inner and outer ends, said portions being formed with aligned openings, and a bolt-guiding tube secured in said openings. 95

10. In a casement window, a sash having hollow upper and lower rails and a hollow vertical rail connecting them, said vertical rail embodying a detachable longitudinal section opposed to the adjacent ends of said 100 upper and lower rails, and mounting means for the sash embodying vertical shafting disposed in said vertical rail, bearings for said shafting having anchoring portions fitting snugly into said upper and lower rails, 105 and means releasably securing opposed sides of said upper and lower rails against said anchoring portions, the sash being removable from the shafting and bearings by removal of said detachable rail section and 110 release of said means.

In testimony whereof we have hereunto affixed our signatures.

FREDERICK H. MILES.
JUDSON D. SWITZER.
